DESIGN FOR A COMBINED CIGARETTE
HOLDER AND ASH RECEIVER

Henry Krohnengold, Bronx, N. Y.

Application September 10, 1946, Serial No. 133,232

Term of patent 7 years

(Cl. D85—8)

To all whom it may concern:

Be it known that I, Henry Krohnengold, a citizen of the United States and a resident of Bronx, in the county of New York and State of New York, have invented a new, original, and ornamental Design for a Combined Cigarette Holder and Ash Receiver, of which the following is a specification, reference being had to the accompanying drawing, forming a part hereof.

Figure 1 is a side view of a combined cigarette holder and ash receiver, showing my new design.

Figure 2 is a top plan view of the same.

Figure 3 is a sectional view taken along the line 3—3 of Figure 1.

Figure 4 is a bottom plan view thereof.

I claim:

The ornamental design for a combined cigarette holder and ash receiver, as shown.

HENRY KROHNEGOLD.
